CLAIM

The ornamental design for a portable fence energizer, as shown and described.

DESCRIPTION

FIG. 1 is a perspective view of a portable fence energizer according to the present invention;

FIG. 2 is a front view of the portable fence energizer according to the present invention;

FIG. 3 is a back view of the portable fence energizer according to the present invention;

FIG. 4 is a left side view of the portable fence energizer according to the present invention;

FIG. 5 is a right side view of the portable fence energizer according to the present invention;

FIG. 6 is a top view of the portable fence energizer according to the present invention; and,

FIG. 7 is a bottom view of the portable fence energizer according to the present invention.

The broken lines shown in the drawings are for the purpose of illustrating portions of the portable fence energizer that form no part of the claimed design.
